BRUSH STRIPPER ATTACHMENT FOR
LIQUID CONTAINERS

Leo L. Kellett, Kansas City, Mo.

Application April 27, 1949, Serial No. 89,858

5 Claims. (Cl. 15—121.3)

1

This invention has to do with a device for automatically removing excess substances from the bristles of a brush as the same is removed from within such substances and to simultaneously shape such bristles as desired for a particular use.

The conventional methods of applying fingernail polish is now generally well known and includes dipping of the brush into the polish, wiping the same at the neck end of a container for such polish to remove excess polish on the bristles and thereupon wiping the brush along the fingernail to apply the polish thereon. Neither an operator nor a home user ever becomes sufficiently skilled to apply the polish evenly on the fingernail to the end that the same will dry quickly and be of a uniform color throughout. If insufficient polish is on the brush to completely coat a fingernail, then it is necessary to redip the brush into the polish and "patch" the fingernail, resulting in several layers of ununiform thickness on a given nail. Consequently the tendency is to assure that enough polish is on the brush to completely cover one nail and the usual result is that the coating is undesirably thick. Such thick coatings do not dry easily, do not have the desired appearance and subsequently, chip and peel more easily and quickly than if a uniform thin coating is initially applied.

So far as I am aware, no means has heretofore been provided that will remove excess polish from the bristles of a brush and at the same time shape and contour the brush so that through one application, a desired coating can be placed on each nail either by an experienced operator or by a home user.

It is the most important object of this invention, therefore, to provide a combination stripping and forming device for the bristles of a brush particularly of the kind used with nail polish or enamel formed to impart but a slight squeezing action to the bristles as the same are removed from the polish and to at the same time, form the bristles into an elliptical or oval cross-sectional contour.

Another important object of the present invention is to provide a stripper of the above mentioned character that constitutes a hollow, conoidal body adapted to be fitted within the neck, of a nail polish bottle and having an elongated, elliptically-shaped opening formed in the bottom thereof for receiving the brush, the body being made from a flexible material that will lightly bear against the outer face of the bristles as the same is pulled therethrough to shape and strip the same.

2

Another important object of the present invention is to provide a stripping and forming device as above set forth wherein the elliptically-shaped opening formed therein, is extended upwardly at each end thereof into the sides of the body for the dual purpose of providing a seal through the polish itself when the brush is in use and to add the desired flexibility to the stripper and former.

10 Other important objects include the way in which the body is formed for use with a conventional container, to be retained therein when the cap is placed on the bottle; the manner of forming the stripper body to assure that the same maintains itself in place when the brush is drawn therethrough; the manner of forming the stripper body to permit easy insertion of the brush thereinto without "ruffling" of the bristles; and many other more minor objects, all of which will be made clear or become apparent as the following specification progresses, reference being had to the accompanying drawing, wherein:

Figure 1 is a substantially central, vertical cross-sectional view of a conventional bottle for nail polish, showing therein a brush stripper attachment made in accordance with my present invention.

Fig. 2 is a side elevational view of the stripper per se.

Fig. 3 is a substantially central, cross-sectional view taken on line III—III of Fig. 2.

Fig. 4 is a cross-sectional view taken on line IV—IV of Fig. 3.

Fig. 5 is an end elevational view of the stripper; and

Fig. 6 is an elevational view showing that end of the stripper opposite to that shown in Fig. 5.

In Fig. 1, a conventional bottle 10 commonly employed for containing fingernail polish or enamel 12, is provided with external threads 14 at the neck 16 thereof for receiving internal threads 18 of a cap 20 for bottle 10.

45 A brush, broadly designated by the numeral 22, is normally disposed within the bottle 10 and is of conventional character in that it is provided with an elongated stem 24 having bristles 26 secured to the lowermost end thereof. The opposite end of the stem 24 is embedded rigidly within the cap 20 and a boss 28 on cap 20 further serves to rigidly support the stem 24.

50 The combination stripping and forming device forming the subject matter hereof, is broadly designated by the numeral 30 and designed to be fitted within the neck 16 of bottle 10 in the manner illustrated in Fig. 1. The device 30 consti-

tutes a hollow, conoidal body 32 having an out-turned continuous flange 34 at the base end thereof or that end uppermost with respect to bottle 10.

This flange 34 is designed to overlap the uppermost open end of neck 16 and the remainder of the body 32 is telescoped within the neck 16 in depending relationship to the flange 34. With the body 32 so positioned within neck 16, and with the cap 20 in place on neck 16, flange 34 is held tightly against the upper end of neck 16 and thereby serves as an air-tight seal for the contents 12 of bottle 10.

The lowermost or apex end of the body 32 is provided with an elongated oval or elliptically-shaped opening 36. Opening 36 extends entirely across the body 32 and upwardly at each end thereof into a pair of opposed egg-shaped apertures 38. It is thus seen that a pair of spaced-apart fingers 40 and 42 are formed in the body 32 by the opening 36 and the apertures 38. The edges of the body 32 forming the longitudinal sides of the oval opening 36 are inclined outwardly as at 44 for purposes hereinafter to be more fully set forth.

As illustrated in Fig. 1, the stem 24 of brush 22 normally passes through the opening 36 when brush 22 is within the bottle 10 and when cap 20 is in place on neck 16. When the cap 20 is removed from bottle 10 and the brush 22 pulled upwardly through the opening 36, outward movement of the body 32 is prevented by the provision of an annular, external groove 46 formed in the body 32 immediately below the out-turned flange 34. That portion of the body 32 immediately below the flange 34 and within which the groove 46 is formed, is designated by the numeral 48 and is substantially circular to conform with the contour of the innermost face of neck 16. The outside diameter of this portion 48 of body 32, with the exception of groove 46, is slightly greater than the inside diameter of the neck 16 to the end that as body 32 is moved into place within neck 16, a tight fit is presented between portion 48 of body 32 and the neck 16 of bottle 10.

The provision of the annular groove 46 presents a dead-air space or pocket and thus serves to further grip the walls of the neck 16 to prevent outward movement of the body 32 with respect to neck 16 when brush 22 is removed from bottle 10.

It is seen from the foregoing that when brush 22 is removed from bottle 10 after the bristles 26 thereof become impregnated and coated with the enamel 12, the inclined edges 44 of the opposed fingers 40 and 42 will bear lightly against the outermost face of the bristles 26 and strip excess enamel 12 therefrom.

It is contemplated that the entire body 32 be made from either a high grade rubber-like material, from a suitable plastic, or from synthetic compositions that will accomplish the purposes hereof. In any event, the material forming body 32 should be carefully chosen and the opening 36 thereof be accurately formed in size and shape to cause removal of excess enamel 12 from the bristles 26 by the fingers 40 and 42 exerting but a slight yieldable pressure on bristles 26. The squeezing action imparted by the fingers 40 and 42 should only be slight since it is desired that the bristles 26 retain a substantial amount of the enamel 12 after removal from bottle 10. Because of the elliptical shape of the opening 36, the bristles 26 will be accordingly contoured in cross-section precisely as desired for the use intended,

i. e., that of application of polish to fingernails. Inasmuch as the ends of the opening 36 extend in an uninterrupted manner into the apertures 38, those portions of the bristles 26 near the ends of the opening 36, will pass freely and excess enamel thereon will be removed only by the uppermost edges of the apertures 38.

After removal of the brush 22 from the bottle 10 and the device 30, the excess substance 12 that has been removed from bristles 26 will automatically close the opening 36 as well as the apertures 38 by forming a light film thereacross. A certain of the substance 12 will collect within the body 32 and flow downwardly for return to the bottle 10 and during such movement of the excess substance, the aforesaid film will close the bottle 10 and prevent entrance of air to the contents 12. When the brush 22 is thereupon placed in use, it will be found that an exact amount of polish has been retained by the bristles 26 and that the operator may apply the desired coating to a fingernail with but one wiping action thereacross. There will be no excess polish 12 on the bristles 26 and, therefore, an even, relatively thin coating, will be applied. Furthermore, there will be a sufficient amount of polish on the bristles 26 to eliminate the necessity of re-dipping to finish a given nail.

It is also to be noted that the device 30 so forms the bristles 26 as is desired by the user and that the bulk of the polish within bristles 26 will be within the heel portion of bristles 26, rather than at the tip end thereof. Consequently, as the brush is successively wiped across the fingernail, most of the polish will be applied at the center thereof and only a light coating will be applied adjacent the cuticle. When it is necessary to redip the brush 22 preparatory to coating another fingernail, it will be found that the bristles 26 will easily enter the body 32 because of the curvature of the walls thereof below portion 48 and that the tip ends of the bristles 26 will easily enter the oval opening 36 without "ruffling" and bending back.

It is to be noted further that when the brush 22 is pulled upwardly between the fingers 40 and 42, the inclined edges 44 thereof will prevent a biting action into the sides of the bristle body 26, permitting movement thereof in a smooth and even movement. Fig. 4 of the drawing shows clearly by dotted lines, the slight amount of outward flexing movement of the fingers 40 and 42 when the brush 22 is moved upwardly and when the bristles 26 thereof pass between the inclined edges 44. The arcuate shape of the walls 55 of body 32 below portion 48 thereof affords sufficient space between neck 16 to permit such slight flexing action.

It is an important consideration that the particular type of bristles 26 with which this invention is concerned, are highly flexible and have a tendency to rebend upon themselves when inserted into the conventional stripping device. These bristles are purposely so formed because of the particular use to which the same are placed and accordingly, the novel feature of the instant stripper in permitting insertion of the bristles without the difficulty of bending back of the bristles 26, renders the stripper commercially practical in forming and removing excess substances from brushes having bristles of this character.

While only one form of my present invention has been illustrated and described, it is apparent that the same is subject to many changes and

modifications and those that fairly come within the scope of the appended claims, are contemplated hereby.

Having thus described my invention, what I claim as new and desire to secure by Letters Patent is:

1. A device for simultaneously shaping the body of bristles of a brush and stripping therefrom an excess of a substance thereon, said device comprising a hollow, open-base, conoidal body formed from flexible material and having an oval opening formed in the apex thereof to form said body of bristles elliptically in transverse cross-section as the same is pulled through the opening; and means on the body for mounting the same within the neck of a bottle-like container.

2. A device for simultaneously shaping the body of bristles of a brush and stripping therefrom an excess of a substance thereon, said device comprising a hollow, open-base, conoidal body formed from flexible material and having an oval opening formed in the apex thereof to form said body of bristles elliptically in transverse cross-section as the same is pulled through the opening, said opening continuing into the sides of the body to present a pair of opposed lips at said apex of the body; and means on the body for mounting the same within the neck of a bottle-like container.

3. A device for simultaneously shaping the body of bristles of a brush and stripping therefrom an excess of a substance thereon, said device comprising a hollow, open-base, conoidal body formed from flexible material and having an oval opening formed in the apex thereof to form said body of bristles elliptically in transverse cross-section as the same is pulled through the opening, said opening continuing at the ends thereof into the sides of the body presenting a pair of opposed ovoid apertures and a pair of opposed lips at said apex of the body; and means on the body for mounting the same within the neck of a bottle-like container.

4. A device for simultaneously shaping the body of bristles of a brush and stripping therefrom an excess of a substance thereon, said device comprising a hollow, open-base, conoidal

body formed from flexible material and having an oval opening formed in the apex thereof to form said body of bristles elliptically in transverse cross-section as the same is pulled through the opening; and means on the body for mounting the same within the neck of a bottle-like container, said means including an out-turned flange on the body remote from said apex adapted for positioning between said neck and a closure for the container to seal the contents of the latter.

5. A device for simultaneously shaping the body of bristles of a brush and stripping therefrom an excess of a substance thereon, said device comprising a hollow, open-base, conoidal body formed from flexible material and having an oval opening formed in the apex thereof to form said body of bristles elliptically in transverse cross-section as the same is pulled through the opening; and means on the body for mounting the same within the neck of a bottle-like container, said means including an annular groove surrounding the body in the outermost face thereof to present a dead-air space between the body and said neck.

LEO L. KELLETT.
